UNITED STATES PATENT OFFICE

HOWARD C. MYERS, OF ONEIDA, NEW YORK, ASSIGNOR OF ONE-HALF TO ISABEL L. LEWIS, OF ONEIDA, NEW YORK

FOUNTAIN WASHING DEVICE

Application filed June 12, 1929. Serial No. 370,226.

My invention has for its object a fountain washing device in connection with combined hot and cold water faucets having a joint pivotally connected or swinging nozzle, particularly a device for washing dishes and supplying at will either hot or cold water to the nozzle or hot or cold water or soapy water or water with any other cleanser therein to a brush or any other desirable device attachable to the outlet of the soap receptacle and has for its object a particularly simple, compact and unitary water dispensing device which can be readily applied in place of ordinary sink faucets, and which is controlled by the swinging nozzle.

The invention consists in the novel features and in the combinations and constructions hereinafter set forth and claimed.

In describing this invention, reference is had to the accompanying drawings in which like characters designate corresponding parts in all the views.

Figure 1 is a front elevation, partly in section, of a fountain washing device embodying my invention.

Figure 2 is a side elevation thereof, partly in section and parts being broken away.

My device comprises, generally, combined hot and cold water faucets having a joint pivotally connected nozzle, a soap receptacle integral with said faucets having an inlet and an outlet for the water and a rotary valve operable by the nozzle for controlling the flow of the water to the nozzle or to the inlet or direct to the outlet of the receptacle.

In the drawings, 1 represents the body or main casting of my device having a conical opening 2 therein for the rotary valve to be hereinafter described.

3 and 4 are hollow branches extending from the main body 1 and are formed at their extreme ends with the hot and cold water faucets 5 and 6, which are connected in the usual manner to the hot and cold water supply.

As here shown, the body 1 is cored at the inner ends of the hollow branches 3 and 4 providing a wall or partition 7 separating said branches from the conical opening 2.

8 is the soap receptacle which is here shown

as part of the main casting 1 and is located above the branches 3 and 4.

9 is a cover held tight in position by means of a wing screw 10 threading through a suitable yoke 11 against the top of the cover, the yoke being detachably interlocked with the body of the soap receptacle, thereby providing an air tight receptacle.

12 is the swinging nozzle here shown as integral with a hollow rotary valve 13 pivotally mounted and held in the conical opening or bore 2 of the body 1 by means of the shoulder 14 on the valve coating with the top of an enlarged counterbore 15 at the lower end of the conical bore 2, and by means of the water tight joint consisting of a packing 16 and a nut 17 threading into the enlarged bore 15.

18 is the inlet for the water passing through to the soap receptacle 8 and 19 is the outlet therefor.

The outlet 19 communicates with a bore 20 entering the body 1 from the back thereof. A coupling 21 is threaded into the outer end of the bore 20 to which may be attached a fountain brush or mop or any desirable attachment.

The inlet passage 18 communicates with the conical bore 2 of the body 1.

22 is a passage communicating with the bore 2 and with the bore 20. This passage 22 is a continuation of the passage 18.

As before stated, the rotary valve is hollow and is here shown as provided with a partition 23 midway between its ends, thus providing it with upper and lower separated conduits 24 and 25.

The lower conduit 25 is provided with ports 26 coating with the ports 27 in the wall 7 for conducting the water from the faucets 5 and 6 direct to the nozzle 12 and the upper conduit 24 is provided with inlet ports 28 for coating with ports 29 in the wall 7 for conducting the water from the faucets to an outlet port 30 which coats with the inlet passage 18 for the soap receptacle or with the passage 22 communicating with the passage 20.

The inlet passage 18 to the soap receptacle is provided with a ball or check valve 31 which prevents the soapy water therein from

seeping down into the upper conduit 24 of the rotary valve.

Owing to the fact that the soap receptacle 8 is air tight and that there is a check valve 5 in the inlet passage 18 leading thereto, the water mixed with the cleanser in the receptacle will not draw in through the outlet 19 except under pressure.

For the purpose of draining said receptacle of the fluid therein, a manually operated valve 32 is provided in the cover 9 of the said receptacle. Opening of the valve brakes the vacuum created in the receptacle and allows the liquid therein to drain off through the passage 19 and out through the coupling 21.

In operation, when it is desired to use the faucets in the regular way with the water passing from either hot or cold water faucet 20 or both to the nozzle, the pivoted nozzle 12 is swung forward or one-quarter turn is made to the right from the position shown in Figure 1.

This movement alines the ports 27 with the ports 26 and disalines the ports 28 and 29 allowing the water to pass to the lower conduit 25 of the rotary valve and thence to the nozzle 12 and closes the entrance to the upper conduit 24 of said rotary valve.

When it is desired to pass the water from the valves 5 and 6 through the soap receptacle, the nozzle 12 is turned to the left as shown in Figure 1, with the ports 26 and 27 out of alinement and the ports 28 and 29 and the port 30 and passage 18 alined, permitting the water to pass from the branches 3 and 4 to the upper conduit of the rotary valve, through the inlet passage 18 by the check valve 31 into the soap receptacle 8 where it mixes with the cleanser therein and passes out through the outlet 19 to the coupling 21.

When it is desired to pass the clear water direct to the coupling 21 without passing through the soap receptacle, the nozzle is turned one-half of a revolution to the right from the position shown in Figure 1, this movement of the nozzle again alines the ports 28 and 29 and disalines the port 30 with the inlet passage 18 and alines the said port 30 with the passage 22.

In this position, the clear water will pass direct from the upper conduit 24 of the rotary valve through the port 30, passage 22, bore 20 and coupling 21.

Obviously, when the nozzle is turned to the left as shown in Figure 1, either hot or cold water or both will pass through the soap receptacle and provide soapy water for any attachment used on the coupling 21.

When the nozzle is turned one-quarter turn or to its forward position, clear water, either hot or cold or both will pass through the nozzle 12 and when the nozzle is turned to the right, clear water either hot or cold or both will pass said attachment.

When the nozzle is turned to any position intermediate to those described, all of the ports will be closed and consequently no water can pass the rotary valve even though the valves 5 and 6 are open.

What I claim is:

1. A fountain washing device comprising a combined pivotally connected hot and cold water nozzle, valves controlling the hot and the cold water, a soap receptacle having an inlet and an outlet for the water and means operable by the nozzle for controlling the flow of the water to the nozzle, or to the inlet or outlet of said soap receptacle.

2. A fountain washing device comprising combined hot and cold water faucets having a joint pivotally connected nozzle, a soap receptacle integral with said faucets having an inlet and an outlet for the water, and means operable by the nozzle for controlling the flow of the water to the nozzle or to the inlet or outlet of the soap receptacle.

3. A fountain washing device comprising combined hot and cold water faucets having a joint nozzle, a soap receptacle integral with said faucets having an inlet and an outlet for the water and a valve operable to control the flow of the water to the nozzle or to the inlet or outlet of the soap receptacle.

4. A fountain washing device comprising combined hot and cold water faucets having a joint pivotally connected nozzle, a soap receptacle integral with said faucets having an inlet and an outlet for the water and a valve operable to control the flow of the water to the nozzle, or to the inlet or outlet of the soap receptacle.

5. A fountain washing device comprising combined hot and cold water faucets, having a joint pivotally connected nozzle, a soap receptacle integral with said faucets having an inlet and an outlet for the water and means operable by the nozzle for controlling the flow of the water to the nozzle, or to the inlet or outlet of said soap receptacle comprising a rotary valve having ports coacting with ports leading to the nozzle or to the inlet and outlet of the soap receptacle.

6. The combination of combined hot and cold water faucets having a joint pivotally connected nozzle and a soap receptacle having an inlet and an outlet for the water connected thereto, and a valve operated by the nozzle and integral therewith to control the flow of the water from the faucets to the nozzle or to the inlet or outlet of said receptacle.

7. A fountain washing device comprising a hot water faucet and a cold water faucet connected to have a combined pivotally connected nozzle, a sealed soap receptacle integral therewith having an inlet and an outlet for the water, a manually operated air valve leading into the soap receptacle, a check valve arranged in the inlet to the receptacle

and a rotary valve integral with the pivotally connected nozzle to be operated thereby to control the flow of the water from either or both faucets to the nozzle or to the inlet or outlet of the soap receptacle.

8. A fountain washing device including a laterally swingable nozzle, a valve controlling the flow of water to the nozzle, a soap receptacle having an inlet passage and an outlet passage, and valve means operable by the lateral swinging of the nozzle for controlling the flow of water through the nozzle, to the inlet passage of the soap receptacle, and to the outlet passage of the soap receptacle respectively.

In testimony whereof, I have hereunto signed my name, at Syracuse, in the county of Onondaga, and State of New York, this 29th day of May, 1929.
